ERNEST A. WOLLITZ, OF OAKLAND, CALIFORNIA, ASSIGNOR OF ONE-HALF TO GILBERT H. PARMELE, OF OAKLAND, CALIFORNIA

CONCEALING AND CARRYING MEANS FOR BURIAL CASKETS

Application filed December 26, 1929. Serial No. 416,372.

The invention relates to means for both concealing a burial casket and supporting the casket for carrying.

An object of the invention is to provide a decorative outer casing for temporary disposal about a relatively undecorated and inexpensive burial casket for concealing the same, only the casket being used in actual interment or cremation and the said casing being used repeatedly with different caskets whereby funeral expenses may be minimized.

Another object is to provide a casing of the class described which is arranged to be placed in or removed from its operative relation to the casket without requiring any displacement of the casket from a set position thereof.

A further object of the invention is to provide an improved unitary holder or carrier for a casket of the class described wherein casket-engaging elements thereof are normally disengaged from the casket and are arranged for operative engagement with the casket by and upon a lifting of the holder, said elements thereafter becoming disengaged from the casket when the latter is set down on a support therefor.

Yet another object is to provide the aforesaid casket concealing and supporting means in a single unitary structure.

The invention possesses other objects and features of advantage, some of which, with the foregoing, will be set forth or be apparent in the following description of a preferred embodiment of the invention which is illustrated in the accompanying drawings, in which:

Figure 1 is a perspective elevation of a casing member embodying the present invention.

Figure 2 is a plan view showing the casing member in operative position over a burial casket, a portion of the casing top being broken away to disclose the underlying structures; also the lining of the casket is omitted.

Figure 3 is a transverse section taken generally at 3—3 in Figure 2.

Figure 4 is a transverse section of the casket after sealing for its final disposal.

Figure 5 is a longitudinal section of the casing and casket assembly.

Figure 6 is an enlarged view of a catch device shown in Figure 3.

Figure 7 is an outside elevation of the device shown in Figure 6.

In many instances, an item which is relatively large among funeral expenses is the cost of the casket or coffin which is buried or cremated with the deceased, an ornate, and therefore expensive, casket being though necessary for the sake of appearances. By means of the present invention, the requirements of appearance are arranged to be satisfied without necessitating the purchase of an ornate casket, such being accomplished by surrounding a plain and inexpensive casket with a removable and ornate casing which may be the property of the undertaker and may be used with the casket on a rental basis. The fact that the removable casing is not part of the casket proper is arranged to be concealed from the mourners, and the costs respecting the casket are materially reduced.

Since the casket will usually be carried in public, means are provided for supporting the casket within the casing for carrying therewith, the casing being provided with handles such as those usually placed on caskets. The latter and other features are incorporated with the casing structure of my invention, and a typical embodiment thereof will now be described.

As particularly illustrated, a casing 8 is provided for enclosing a casket 9. The casket 9 may be a plain rectangular box having sides 11, ends 12, and a bottom 13 fixed together to provide a receptacle having an open top, a lid 14 being provided for screwed-down mounting at the top of the casket for sealing a body therewithin; the lid 14 is shown in place in Figure 4. In the present instance, the casket 9 is shown as of wood. The casing 8 is open

at the bottom, and includes side walls 15 and end walls 16 cooperative to define a space for receiving the casket 9; in this manner, the casing is arranged to be placed about the casket with its walls in spaced relation from opposed walls of the casket. Preferably, and as particularly shown, the bottom casing edges are arranged to engage the same supporting surface 17 on which the casket rests; in this manner, the casing and casket are independently supported from said surface and the casing may be operatively installed or removed vertically without moving the casket from a set position thereof; this feature is particularly valuable in removing the casing from about the casket just before interment or cremation, as from a grave bottom or conveyor platform. The casing 8 is desirably constructed entirely of metal whereby it may be most readily kept clean and sanitary.

Preferably, and as shown, the casing 8 is provided with a cover 18. In the present instance the cover 18 is hinged to a casing side wall 15, and is provided with an opening 19 having a suitable closure 21. The opening 19 it is noted, is provided for viewing the face of the deceased, and the closure 21 may be transparent or opaque, as desired; as shown, the closure 21 comprises an opaque plate hinged to the cover at an edge of the opening 19. Externally, the casing walls and top are formed in a more or less decorative manner, and the handles 22 and 23 mounted at the casing sides and ends respectively complete an assembly which appears as a usual decorated casket. The exact degree and character of decoration provided by the casing and handles is, of course, a matter of design, it being essential only that the appearance of the casing be pleasing and lacking in cheapness.

As is usual, the casket is lined with padding 24, and for present purposes the free edge portion 25 of said padding extends from and over the top edges of the casket sides and between said sides and the inner faces of the casing wall to conceal the fact that the casing is not a part of the casket, this feature being particularly disclosed in Figures 3 and 5. In this manner, the casket is entirely concealed within the casing and the appearance of the assembly is that of the casing. It is noted that the use of the casing cover is not essential to the present assembly as far as concealment of the casket is concerned. When the casket lid 14 is to be applied, the lining portion 25 is folded within the casket space and over the body therein as is shown in Figure 4.

For lifting and moving the casing and casket assembly as a unit, means are provided for fixing these members together when and as required. In the present instance, said means are controlled in accordance with the

disposal of the side handles 22 by which the casing is arranged to be carried by pall-bearers. As particularly shown, the handles 22 each comprise a plurality of arms 31 hinged in a line to and along each casing side 15 and connected at their free ends by means of a bar 32 which provides a common handle grip for grasping by the hands of a number of persons positioned along and beside the casket casing. Heretofore, it has been a customary feature in handles of the present type that the handles depend beside a casket when not in use and be swung outwardly to an operative position, said latter position being determined by the engagement of the arms with a fixed stop on the casket side. In the present instance, the handles also swing, but the swinging of a handle to an operative position with respect to the casing is arranged to actuate one or more levers 33 forming part of the catches for engaging the casket whereby a lifting of the casing from the supporting surface therefor by means of the handles 22 is arranged to effect a lifting of the casket with it.

As particularly brought out in Figures 3, 6 and 7, each arm 31 is pivoted on a pin 34 extending between extending ears 35 of a plate 36 mounted on the casing wall 15. The lever 33 is also pivoted on the pin 34, and the plate 36 and wall 15 are provided with registering openings between the ears 35 for the inward extension of the lever 33 from its pivot point. The position of the lever 33 is determined by that of the arm 31 and appropriate engagement of the arm and lever is therefore provided for. In the present instance, the pivoted end 37 of the arm 31 is provided with parallel and plane faces 38 and 39 at inner and outer opposite sides thereof and said faces are connected by a cylindrically curved surface, the planes of the faces 38 and 39 being parallel to the pivotal axis of the arm. For mounting the lever 33 on the pin 34, the lever is provided with a socket 41 for receiving the arm end therein, with end walls 42 of the socket perforated to receive the pin. Preferably, and as shown, a certain amount of free swinging movement of the pivoted arm end 37 in the socket 41 is provided for, and for this reason, the socket side faces 43 and 44 opposite the arm faces 38 and 39 respectively are angularly related whereby one or the other of the socket faces is spaced from the opposed arm face when the arm is in one or the other of its extreme positions in the socket. It is noted that the lever portions providing the faces 43 and 44 are lever arms of the lever 33 whereby the inner arm 45 of the lever is arranged to be positively urged downwardly when the handle arm 31 is swung outwardly toward its operative position, and is thereafter urged upwardly when the handle arm 31 swings downwardly to its normal and inoperative position.

5 The lever arm 45 operates a swinging catch bar 46 provided at its lower end with a hook 47 for engagement beneath the bottom of the casket. As particularly shown, the lever arm 45 is provided with a socket or slot 48 at its extremity for the reception of an end 49 of the bar 46 whereby the bar will be rocked as the lever is rocked. Preferably, and as shown, the bar 46 is pivoted between the sides 10 of a member 51 of generally channel section, said member being fixed in upright position below the lever opening in the wall 15 and at the inner side of said wall. To provide for guiding the casing as it is lowered over the casket, the lower end edges of the sides of the members 51 are preferably bevelled as shown at 52 in Figures 3 and 6.

15 It will now be noted that the operative relation of the parts of the catch mechanism described is such that an outward swinging of a handle to its operative position depresses the lever portions 33 to so rock the catch bars 46 as to engage the hooks 47 thereof beneath the casket bottom, the side of the casket serving as a stop for the movement of the bar, lever and handle in turn. To facilitate said engagement of the hook 47 beneath the casket, the latter is preferably mounted on blocks 53, said blocks either being loose or fixed to 20 the bottom of the casket as may be desirable and holding the casket very slightly above the latches to allow their free swinging beneath the bottom. After the opposite sets of catches are engaged, the casing and casket 25 may be lifted together for transportation, the lift being accomplished through the handles. When the casket and casing are again set on a floor or other surface, the blocks 53 being in place, the casing is lowered to release the 30 hooks 47 and the swinging of the handles to their depending, and inoperative, positions positively moves the hooks from beneath the casket, it being noted that the members 51 then enclose the catch portions of the bars 45 35 as guards therefor, and that the latter disposal of the hooks is a normal one for the same.

40 While in the present instance the casing 8 functions both as a concealing and lifting means for the casket, it is obvious that where concealment is not required or desired a casket engaging mechanism such as that described might be incorporated with the structure of an open crate or frame for disposal about 45 the casket, said frame then functioning solely as a carrying holder for the casket. The handles 23 do not in any way engage the casket when they are extended for use, and so are used for removing the casing from 50 around the casket.

55 From the foregoing description taken in connection with the accompanying drawings, the advantages of the construction and method of operation will be readily understood by those skilled in the art to which the inven-

tion appertains, and while I have described the principle of operation, together with the device which I now consider to be the best embodiment thereof, I desire to have it understood that the device shown is merely illustrative, and that such changes may be made, when desired, as fall within the scope of the appended claims.

Having thus described my invention, I claim as new and desire to secure by Letters Patent of the United States the following:

1. In combination with a casket, a casing for disposal about said casket, lifting handles at the exterior sides of said casing, arms fixed to said handles and hinged to the sides of the casing to permit the handles to be swung in a vertical plane from depending and inoperative positions thereof to operative positions of transverse extension from said sides of the casing, catch bars mounted at the interior sides of said casing between the same and the sides of the casket, said catch bars being pivotally mounted for swinging movement laterally of the casket, 80 said catch bars having hooked ends for engagement beneath the bottom of the casket, and an operative connection between said handles and said catch bars whereby swinging movement of the handles to operative 85 positions will engage the catch bars with the casket and swinging movement of the handles to inoperative positions will disengage the catch bars from the casket.

2. In combination with a casket, a casing for disposal about said casket, lifting handles at the exterior sides of the casing, arms fixed to said handles and hinged to the sides of the casing to permit the handles to be swung in a vertical plane from depending and inoperative positions thereof to operative positions of transverse extension from said sides of the casing, catch bars mounted at the interior sides of said casing between the same and the sides of the casket, said catch bars being pivotally mounted for swinging movement laterally of the casket, said catch bars having hooked ends for engagement beneath the bottom of the casket, levers pivotal about the same axis as said arms and projecting through the casing, the inner end of said levers being bifurcated and engaging the upper ends of the catch bars whereby swinging movement of the levers will cause operation of the catch bars, and means where- 100 by operation of the handles will cause operation of the levers and consequently operation of the catch bars.

105 In testimony whereof, I affix my signature.

110 ERNEST A. WOLLITZ.
